UNITED STATES PATENT OFFICE

2,577,400

REFRACTORY LINING FOR DOMESTIC FURNACES

William N. Butterworth, Shaker Heights, Ohio,
assignor to General Refractories Company,
Philadelphia, Pa., a corporation of Pennsylvania

Application May 3, 1948, Serial No. 24,834

2 Claims. (Cl. 158—1)

1

The object of the invention is to provide improvements in refractory linings for furnaces, and more specially in the burner and runner bricks or tiles which line the fire box or combustion chamber of a domestic or similarly small furnace.

In most furnaces of this broad class fuel oil is injected into the fire box in a substantially atomized condition under pressure, in order that the oil being in a semi-gaseous or vaporous state will readily unite with the air and contribute its heat of combustion to the heat-absorbing surfaces of the furnaces. However, except under the most ideal circumstances the oil vapor frequently carries with it small globules of oil in unvaporized or liquid form, while during the initial period of firing, when the furnace is still at least relatively cold, the prevalence of such globules is much more pronounced. Furthermore, as each of said globules is ignited and consumed from its outer surface inwardly, instead of by instantaneous combustion as in the case of more volatile liquids such as gasoline, it requires an appreciable time for such burning to take place, and being in the usual forced draft of such a furnace a portion of the liquid phase of oil is carried partially or even entirely up the chimney during and before completion of its combustion. In order to ignite such globules and even the more finely subdivided vapor particles, so that substantially complete combustion takes place within the firebox, and a minimum of resulting heat is carried wastefully up the stack or chimney, efforts are constantly being made to provide as quickly as possible and maintain incandescent surfaces against which the oil impinges, whether in liquid, vapor or gaseous form, whereby when such fuel comes into direct contact with such high temperature surfaces it will be thereby instantly ignited and consumed while still within the fire box with the aid of the oxygen-laden air that is present in the draft. Under such conditions, not only is less fuel wasted and more effective heat realized, but little or no soot is deposited under the cooler parts of the furnace and chimney to cover and insulate the same and simultaneously produce a fire hazard.

Another object therefore is to provide a type of refractory brick or tiles having a radially inwardly directed surface that is characterized by spaced lugs, which may be of any desired shape, size and arrangement, but which preferably have relatively small terminal or other portions that readily attain incandescence almost immediately upon ignition of the first fuel to be injected into the fire box, and which thereafter continue in such state of incandescence as long as the consumption of fuel continues. Such lugs may be

2

of any desired shape, but preferably taper inwardly away from their supporting wall as in the shape of cones, pyramids, or frustums of the same and while they may be substantially equally spaced upon the surface of said supporting wall, may instead be more closely arranged within a space that forms the target area for the burner and is approximately concentric therewith.

A further object is to provide a substantially 10 cylindrical, or at least a peripherally closed arrangement of runner tile or brick which is broken only by the interposition of a single brick (or a pair of adjacent bricks) having an aperture through which the usual burner extends or projects, and by means of which the fuel is injected into the interior of said arrangement or assembly, and said runner tile being provided with the inwardly directed preferably tapering lugs which when heated to a high temperature radiate their 15 heat upwardly through and from the upper open end of the assembly to the heat-absorbing surfaces of the furnace above the same. It is to be understood that instead of the injection of fuel by means of a pressure or other burner through 20 the aperture referred to, the hollow assembly of lug-carrying tiles may surround a rotary burner of the type employed in some installations, in which case the fuel projected by such burner is still directed substantially horizontally against a circumferentially extending area upon the inner 25 lugged surfaces of the said tile, and in such case it is unnecessary to include one or more apertured tile as in the case of the so-called gun-type burners. In either such construction, arrangement and relationship of burner and tile, 30 a high degree of turbulence is created in the intermixed fuel and air, as the combination thereof mushrooms against the lugged area of the surface of the surrounding tile.

With the objects and principles of operation 35 thus briefly stated, the invention comprises further details of construction, assembly and operation hereinafter fully brought out in the following description, when read in conjunction with the accompanying drawings, in which Fig. 1 is a front elevation of an assembled unit of the improved tile comprising one embodiment of the invention; Fig. 2 is a plan view of the same; Fig. 3 is a plan view of one of the improved runner tile per se; Fig. 4 is an inner elevational 40 view of the same; Fig. 5 is a plan view of a segmental tile that comprises one-half of the base upon which the cylindrical assembly rests, the other half tile of said base being indicated in dash and double dot lines, in order to indicate 45 a normal assembly of a pair of said base tiles;

and Fig. 6 is an elevation of the base half tile shown in Fig. 5.

Referring to the drawings, it will be assumed that a complete assembly of the improved tile comprises a pair of base sections, a pair of burner-opening tile and four runner or segmental liner or runner tiles, it being understood that the base might instead comprise a single tile while the burner aperture might extend substantially centrally through a single tile instead of being defined by a pair of complementary recesses in a pair of adjacent tiles, and that there may be any desired number of runner or liner tile, depending upon the internal diameter of the furnace fire box, the thickness of said tile and the chords found to be most economical.

In the present example of construction and assembly, each of the tile of said base comprises a semi-circular bottom portion 1, upon which is superimposed a semi-circular upwardly extending integral projection 2, providing a semi-circular shoulder 3 that is sufficiently removed radially inwardly from the corresponding portion of the periphery of said bottom portion to provide a correspondingly semi-circular supporting surface 4 for the lower end 5 of the said runner tiles when assembled thereon. Thus, a pair of these base tiles when each is 180° in extent cooperate to provide a complete circular base, as indicated by both the solid and broken lines in Fig. 5.

In the design herein illustrated, two complementary burner tiles 6 are shown, each being provided with a semi-circular cutout 7 which in practice cooperate to provide a so-called burner opening through which at least the nozzle of a gun-type burner normally extends, or through which in any case fuel is injected under pressure into the interior of the tile assembly. It should be understood that whereas most furnaces today employ liquid fuel, such as a medium grade of fuel oil, that is forced into the fire box from a small nozzle orifice under sufficient pressure to atomize it, gas may be used instead, while it is possible to use finely powdered coal dust.

The lining of the fire box comprises other than said burner tiles, a plurality of segmental tiles 8 that cooperate with said burner tiles and with one another, each of these tiles being provided upon its radially inner surface with a plurality of lugs 9 that are formed integrally with the body of the tile and which are preferably of such shape and inward taper as to offer a terminal portion of relatively low volume that extends well into the interior of the hollow cylinder when the tiles are assembled, and accordingly into the region of greatest heat of the swirling gases of combustion, with the result that these terminal portions of the lugs attain incandescence upon being encountered by the flame from the burner, and at the same time accelerate the rise in temperature of the inner surface of the body of the tiles, in addition to effecting a substantial increase in the surface area of the tiles, thereby providing high-temperature surface areas which materially aid in igniting the fuel as it impinges thereupon.

In the case of fuel oil, it is only under the most ideal conditions that the liquid is thoroughly atomized, as it enters the tiled enclosure of the fire box after the latter has become thoroughly heated and combustion is considered substantially perfect and even in such installations combustion is far from perfect while the lining and general furnace interior are still at a low temperature, as when starting the furnace. Furthermore, the best burner installations deteriorate

in time and require attention to clean and adjust them, as well as accumulating soot to a partial degree at least, so that efforts have long been made to insure as complete combustion of fuel as possible when conditions are less than the degree of perfection desired, realizing that when conditions are correct the combustion will continue to be no less efficient than initially.

It has long been realized that perhaps all fuels and certainly fuel oil are ignited and burned much more rapidly, and therefore with less tendency towards incomplete combustion and resulting smoke and soot, if brought into more or less direct contact with an incandescent surface, and that it is desirable to provide such incandescence as soon as possible after fuel is first directed into a relatively cool fire box interior; also that if such incandescent surfaces could be made of a shape to create and maintain turbulence and thereby accelerate the intermingling of the gaseified fuel and incoming air, the complete combustion of the fuel would be considerably more nearly instantaneous, with proportionately less fuel wasted up the stack or chimney and less accumulation of soot resulting.

Accordingly, the radially inner surface of each of the runner tile is provided with both vertically and horizontally spaced, inwardly projecting lugs, teats or knobs, which may be of substantially uniform and regular arrangement over the surface of the tile, or instead may be more closely arranged at that portion of the area of said tile directly opposite and in general alignment with the burner opening. In Fig. 1 the concentration of such lugs is shared by two adjacent runner tile, being bisected by the vertical joint between said tiles, while in Figs. 3 and 4 such concentration is shown as being located substantially centrally of the single tile there shown.

The joints between adjacent tiles are preferably irregular in shape, so as to thereby overlap and prevent the escape of high temperature gases radially outwardly past the tile and into direct contact with the inner metallic surfaces of the surrounding furnace. While the shape of these joints may be of whatever form is desired, each is here shown as comprising a radially outer, diagonally extending section 10 that terminates inwardly in a short, circumferentially extending section 11 from which a radial section 12 terminates inwardly at the inner surface of the adjacent tiles, the angular joint surfaces of one side of each segmental tile being complementary to that of the tile next adjacent thereto.

When adapting the invention to rotary burners, no frontal aperture is provided as the rotary element revolves upon a vertical axis centrally disposed within the fire box, so that the flame strikes the lining tiles in a substantially circular line of uniform elevation, and in that case the lugs may be arranged more closely together about the internal periphery of the lining at an elevation intermediate the vertical limits of the runner tiles, which in such a case constitute the entire assembly, since no so-called burner tiles are needed.

Having thus described my invention, what I claim and desire to protect by Letters Patent of the United States is:

1. In a furnace, the combination of a substantially cylindrical assembly of segmental tiles having a burner opening in one side of said assembly adapted to admit a stream of fuel in fluid form directed against a restricted portion of the area of the opposite side wall of said assembly, said

tiles through at least a major portion of said assembly being provided with radially inwardly directed tapering lugs that tend to incandesce in and by virtue of the heat of the flame of burning fuel, said lugs being more closely grouped together in an area diametrically opposite said opening.

2. A hollow refractory lining for the firebox of a furnace having a burner-opening in one side, and comprising a plurality of tiles having a joint substantially opposite said opening, a major portion of the inner surface of said lining being provided with inwardly tapering incandescable cones, said cones being more closely grouped together in an area diametrically opposite said opening and upon the opposite sides of said joint.

WILLIAM N. BUTTERWORTH.
